M. MEYERSON

TEMPORARY BINDER

Filed June 9, 1926

UNITED STATES PATENT OFFICE.

MAX MEYERSON, OF NEW YORK, N. Y.

TEMPORARY BINDER.

Application filed June 9, 1926. Serial No. 114,843.

This invention relates to a temporary binder, and an object of the invention is to provide a binder which is especially intended for the temporary holding of telephone books and the like, although it will be understood of course that the binder is equally well adapted for the holding of other books.

A further object is to provide a binder which may be connected with the book in a very simple and efficient manner, the connecting elements being firm and substantial and unlikely to become accidentally disconnected, while yet being readily and easily disconnected by manual manipulation whenever desired.

A further object is to provide a binder which may be used for the retention of a single book or several books simultaneously.

Other objects and aims of the invention, more or less specific than those referred to above, will be in part obvious and in part pointed out in the course of the following description of the elements, combinations, arrangements of parts and applications of principles constituting the invention; and the scope of protection contemplated will be indicated in the appended claims.

In the accompanying drawings which are to be taken as a part of this specification, and in which I have shown merely a preferred form of embodiment of the invention:

Fig. 1 is a plan view of a binder constructed in accordance with this invention.

Fig. 2 is a sectional view substantially upon the plane of line II—II of Fig. 1.

Fig. 3 is an end view of the binder, and

Fig. 4 is a perspective view of one of the retaining members employed.

Referring to the drawings for describing in detail the structure illustrated therein the reference characters L and G indicate the two cover portions of the binder, while the reference character H indicates the back portion of the binder. In the instance illustrated these three parts are made from a single piece of sheet material such as fibre board or the like formed with appropriate creases as 1—1 therein at opposite sides of the back portion and providing the hinges by which the cover portions are connected with the back portion. It will be understood how-

ever that any other structure may be resorted to for providing the cover and back portions and hinge connections therebetween.

At opposite ends of the back portion H 55 suitable brackets or holders as 2—2 are provided. These are preferably of identical construction and manner of attachment and use. They are each formed from a single piece of sheet metal bent to provide a base 60 portion 3 and a shoulder portion 4 upstanding from the base portion. The base portion is adapted to be held rigidly fixed to the back portion H of the fibre as by means of rivets or the like as 5 so that the shoulder 4 projects upwardly from the back in close proximity to the end edges 6 of the back.

The shoulder portions 4 are made of double thickness, that is the metal from which they are formed is first bent upwardly to provide a relatively inner wall portion 7, and thence downwardly again to provide a relatively outer wall 8. The two walls 7 and 8 are spaced an appreciable distance apart leaving an opening as 9 between them and incidentally providing a broad upper rounded surface as 10 upon the shoulder which is both attractive and smooth when engaged by an operator's fingers or otherwise. The lower edge as 11 of the wall 8 is preferably brought 70 into immediate contact with the surface of the back H so that it thus constitutes a supporting leg receiving reinforcement from the back H to prevent likelihood of any outward bending of the shoulder 4, as about the angle 75 connection 12, during the use of the binder.

The wall 7 of the shoulder 4 is provided with one or more apertures as 13 therethrough, and the wall 8 is likewise provided with one or more apertures 14 arranged to mate the apertures 13 of the wall 7, that is the apertures 13 and 14 in these spaced walls form pairs in alignment longitudinally of the back H.

Each pair of apertures is adapted to receive 95 one of the retaining members 15 as illustrated in Fig. 4.

All of the retaining members employed are of identical construction and manner of use. They each consist of a pair of spring 100 arms as 16—16 connected together and suitably pointed as at 17 at one end, which for

convenience will be referred to as their inner end. These arms normally spread apart from their inner ends to their outer ends and at their outer ends are turned oppositely away 5 from each other to provide stop shoulders 18—18 thereon.

Adjacent each of these stop shoulders the 10 arms are curved away from each other so as to provide inclined shoulders 19—19 thereon opposed to the shoulders 18.

After the book has been placed in position 15 within this binder, as illustrated by the dotted lines 20 in Fig. 2, that is with its binder portion between the shoulder portions 4 of the 20 holders 2—2, one or more retaining members are inserted through the apertures 13 and 14 of each of the holders 2—2, said retaining members being inserted by introducing their pointed ends 17 inwardly through the openings 14 and 13 until the shoulders 19 snap into the openings 9 and the shoulders 18 engage 25 against the outer surface of the wall 8, the greater portion of the length of the retaining members being thus introduced into 30 retaining position between the leaves of the book, as will be readily understood. The snap action of the shoulders 19 is occasioned by the fact that the width of the openings 14 is less than the normal width of the outer 35 end of the retaining member so that during the movement of the retaining member inwardly the two arms of the retaining member are sprung toward each other and consequently generate a spring pressure which functions to snap the shoulders 19 away from each other as the thickness of the wall 8 is passed.

By threading the retaining members through the openings 13 of the spaced walls 40 7 the end surfaces as 21 of said openings 13 serve, in conjunction with the end surfaces 22 of the openings 14, to hold the retaining members in parallel relation with the surface of the back H and thus efficiently retain the 45 book against dislodgement.

When it is desired to release one or more of the retaining members it is simply necessary to force the retaining member outwardly, either by pressure against its inner end 50 or by a pull upon its outer end as by the use of a knife blade or the like inserted beneath a shoulder 18. The inclined shoulders 19 will cam outwardly through the opening 14 when sufficient strain is applied, whereupon the 55 book may be readily lifted away.

In instances where it is desired to hang the binder on a wall hook or the like, as is frequently the case in the care of telephone books, one end portion of the back H may 60 be formed with a reinforced opening 23 into which a ring hook as 24 is engaged for this purpose.

As many changes could be made in this construction without departing from the 65 scope of the invention as defined in the fol-

lowing claims, it is intended that all matter contained in the above description or shown in the accompanying drawings, shall be interpreted as illustrative only and not in a limiting sense.

Having thus described my invention, what I claim as new and desire to secure by Letters Patent is:—

1. A temporary binder comprising a back portion, a pair of holders connected with 75 said back portion adjacent opposite ends thereof, said holders being each formed from a piece of sheet-metal bent to provide inner and outer walls spaced apart in the direction of the length of said back portion, said walls 80 having openings therethrough, and retaining members extending through said openings, said retaining members having snap-acting parts to releasably hold them within said openings.

2. A temporary binder comprising a back portion, a pair of holders connected with 90 said back portion adjacent opposite ends thereof, said holders being each formed from a piece of sheet-metal bent to provide inner 95 and outer walls spaced apart in the direction of the length of said back portion, said walls having openings therethrough, and retaining members extending through said openings, and said retaining members each comprising 95 a pair of spring arms having shoulders thereon arranged to snap into said openings for thereby releasably holding the retaining members in retaining position.

3. A temporary binder comprising a back 100 portion, a pair of holders connected with the back portion adjacent opposite ends thereof, retaining members carried by said holders, one of said holders having an opening there-through in the direction of the length of the 105 back portion, and the retaining member of said holder extending through said opening, said retaining member comprising a pair of spring arms connected together at their entering end and said retaining member having 110 a shoulder thereon for engaging a part of the holder to hold the retaining member in retaining position.

4. A temporary binder comprising a back portion, a pair of holders connected with 115 the back portion adjacent opposite ends thereof, retaining members carried by said holders, one of said holders being formed from a piece of sheet-metal bent to provide inner and outer walls spaced apart in the 120 direction of the length of the back portion, said walls having aligned openings there-through, and the retaining member for said holder having a transversely expansible portion extending through said aligned openings 125 with an enlargement thereon arranged to stand in the space between the inner and outer walls to thereby hold the retaining member against displacement.

5. A temporary binder comprising a back 130

portion, a pair of holders connected with the back portion adjacent opposite ends thereof, retaining members carried by said holders, one of said holders being formed from a piece of sheet-metal bent to provide inner and outer walls spaced apart in the direction of the length of the back portion, said walls having aligned openings therethrough, and the retaining member for said holder comprising a pair of spring arms having enlargements thereon arranged to snap into the space between the inner and outer walls of the holder for thereby releasably holding the retaining member in retaining position. ¹⁰

In testimony whereof I affix my signature.

MAX MEYERSON.
